UNITED STATES PATENT OFFICE.

RICHARD A. BERGER, OF NEW YORK, N. Y., ASSIGNOR OF ONE-HALF TO
WESLEY S. BLOCK, OF SAME PLACE.

PACKAGE-WRAPPING MACHINE.

SPECIFICATION forming part of Letters Patent No. 643,622, dated February 20, 1900.

Application filed January 5, 1898. Renewed June 28, 1899. Serial No. 722,187. (No model.)

To all whom it may concern:

Be it known that I, RICHARD A. BERGER, a citizen of the United States, residing at New York, (Brooklyn,) in the county of Kings and 5 State of New York, have invented certain new and useful Improvements in Package-Wrapping Machines, of which the following is a full, clear, and exact specification.

This invention relates to that class of machines which are designed to apply wrapping material to articles of merchandise, particularly that type wherein each wrapper or wrapper-section is folded longitudinally upon the article and has its ends down folded, then 10 laterally folded or tucked in, and, finally, lap-folded over the downfolded and laterally-folded or tucked-in parts to completely inclose the article and protect it from the effect of atmospheric influences.

20 The present invention is intended specially for applying wrapping material to blocks of chewing-gum, each block comprising five superimposed layers, more or less; but I wish it clearly understood that the invention is 25 capable of being practicably and successfully used for applying wrapping material to various articles of merchandise—such as soap cakes, chocolate, and the like—in such manner that the articles are completely inclosed by 30 folding the wrapping material longitudinally around the same, downfolding portions of the ends, laterally folding or tucking in parts of the ends, and lapfolding the other parts of the ends upon the lateral folds or tucks.

35 The chief object of my present invention is to provide novel means whereby the article to be inclosed within a wrapper is under perfect control of parts of the machine and cannot be displaced or shifted relatively to the wrapper 40 from the time it is placed in proper relation to the latter and is completely inclosed thereby.

The invention also has for its object to provide a package-wrapping machine with wrapping material in the form of webs wound on reels and with novel means for drawing the webs longitudinally the proper distance at regular intervals to place the wrapping material over the articles which are to be inclosed within wrappers severed from the webs at regular intervals.

The invention also has for its object to provide a package-wrapping machine wherein the wrapping material proper is in the form of a web wound upon a reel, and the binder 55 is also in the form of a web wound upon a reel, and means are provided for severing a wrapper-section from the webs and subsequently shifting the binder of the wrapper-section into correct position, so that the wrapper-section proper will be of a greater length than the binder to enable the ends of the wrapper-section to be properly folded and the binder to be applied around the article to bind the whole in position. 60

The invention also has for its object to provide a package-wrapping machine with new and improved folding devices for folding the longitudinal edges of the wrapper-section one upon the other, turning down portions of the 70 ends of the wrapper, tucking in parts against such turned-down portions, and subsequently lapfolding portions upon the tucked-in parts.

The invention also has for its object to provide a package-wrapping machine with wrapping material in the form of a plurality of webs, one of which constitutes a binder-web and is provided with adhesive along one edge and novel mechanism for moistening the adhesive edge of the binder-web, so that when 80 the article is subjected to the action of the folding mechanism the moistened adhesive edge is secured and a perfect package is produced. 75

The invention also has for its object to provide a new and improved device which serves to secure the adhesive part of the wrapping material, to partially fold the ends of the latter, to remove the completed package from the folding box or chamber, and to place it 90 in a position from whence it may be carried or conveyed to any point desired. 85

The invention also has for its object to provide a new and improved arm which is provided with wings that serve first to form parts 95 of the folds at the ends of the package and to subsequently lift the completed package from the folding box or chamber and deliver it at a point from whence it may be carried or conveyed to the place desired. 100

The invention also has for its object to provide new and improved feed mechanism for

advancing the webs of wrapping material to place the leading edges thereof in position to be seized by nipping mechanism by which the webs are drawn longitudinally in proper 5 relation to the articles which are to be inclosed within wrappers.

The invention also has for its object to provide a brake mechanism automatically operated at proper intervals to arrest the momentum of the reel on which the web of tin-foil is wound, whereby an undue quantity of this web will not be unwound, due to the momentum of the reel, at the time that there is a pause in the longitudinal movement of the 15 web and a wrapper-section is being severed.

The invention also has for its object to generally improve package-wrapping machines and to provide a machine of this character which will practicably and successfully apply 20 wrappers to articles of merchandise and fold in the ends in such manner as to entirely inclose the articles.

To accomplish these objects, my invention involves the features of construction, the 25 combinations or arrangements of parts, and the principles of operation hereinafter described and claimed, reference being made to the accompanying drawings, in which—

Figure 1 is a top plan view of my improved 30 package-wrapping machine, omitting the reel which carries the tin-foil and waxed paper. Fig. 2 is a longitudinal sectional view taken on the line 2 2, Fig. 1, omitting the reels which carry the webs of wrapping material. Fig. 2^a is a diagram indicating the nippers as having drawn or pulled the webs longitudinally and the shear-blades closed to sever the webs. Fig. 2^b is a similar view indicating the nippers as having adjusted the tin-foil, waxed 40 paper, and binder into position over the article which is to be wrapped, the two gripping and transferring jaws being nearly in position to grip the article and the wrapper to transfer them to the folding-box. Fig. 3 is a front elevation, omitting the reel which carries the tin-foil and waxed paper. Fig. 4 is a sectional end elevation, the plane of section being substantially on the line 4 4, Fig. 1. Fig. 4^a is a detail view showing portions of the perpendicular rack-bars by which the pressing and lifting arm is swung and its folder-wings are opened and closed, also showing the cam and levers which coöperate with these rack-bars. Fig. 5 is an elevation looking at the left-hand end of the machine. Fig. 6 is a transverse sectional view taken on the line 6 6, Fig. 1. Fig. 7 is a detail longitudinal sectional view taken through the folding-box and the pressing and lifting arm. Fig. 8 is a broken detail plan view of the folding-box. Fig. 9 is a sectional plan view showing the plate with its racks which actuate the pinions to turn the oscillatory tuckers or side-angle folders. Fig. 10 is a detail perspective 65 view of one of the tuckers or side-angle folders, showing its spindle and pinion. Fig. 11 is a detail view showing the clamp-plate of the

folding-box and the bottom plate thereof, which carries the end-folder wings of the folding-box. Fig. 12 is a detail vertical sectional view showing the pressing and lifting arm in a perpendicular position and in the act of swinging to the receiving-table, where the wrapped article is deposited. Fig. 13 is a detail broken elevation looking at the pressing 70 and lifting arm and its actuating rack-bars from the left-hand end of the machine. Fig. 14 is a detail sectional view showing the manner in which one end of the pressing and lifting arm is supported and rigidly connected 75 with one pinion and loosely mounted on the hub of the other pinion. Fig. 15 is a detail side elevation showing the means for positively rotating the feed-rolls by which the binder-web and the tin-foil and waxed-paper webs are fed forward toward the nippers 80 which pull these webs longitudinally. Fig. 16 is a vertical sectional view taken on the line 16 16, Fig. 15. Fig. 17 is a detail transverse sectional view showing the shear-blades, 85 the links by which they are operated, the upper and lower guides between which the webs of wrapping material pass, and the moistening-roll for moistening the adhesive margin of the binder-web. Fig. 18 is a detail rear-end elevation showing the two reels, the brake for the reel which carries the tin-foil and waxed paper, the pressing-finger, and the gears which gear together the feed-rollers that advance the tin-foil and waxed paper. Fig. 19 is a rear elevation showing the devices 90 whereby the shear-blades are operated to sever the webs at the proper time. Fig. 20 is a detail perspective view of the magazine-slide by which the articles are successively 100 removed from the magazine and placed in position beneath the wrapping material. Fig. 21 is a detail perspective view of the two horizontally-moving slides which carry the nipping-jaws. Fig. 22 is a sectional plan view to 105 show the manner in which the yoke-frames of the gripping and transferring jaws are mounted. Figs. 23 to 28, inclusive, are detail views of vibratory lever-arms and cams for moving the same to actuate parts of the 110 machine, as will fully hereinafter appear. Figs. 29 to 35, inclusive, are views showing the manner in which the wrapper composed of tin-foil, waxed paper, and a binder is folded to entirely inclose the article of merchandise. 115

In order to enable those skilled in the art to make and use my invention, I will now describe the same in detail; but inasmuch as I believe that the operation of the various parts of the machine will be more readily understood by first describing the manner in which the folds of a wrapper are disposed with relation to the entire package, I will first describe the folds without reference to the mechanism whereby these folds are produced. 125 For this purpose reference is first made to Figs. 29 to 35, inclusive. In Fig. 29 a wrapper is represented as laid upon the upper side of an article, such as a block of chewing gum,

the article or chewing-gum being indicated by dotted lines. The wrapper is composed of three layers, first, a layer 1 of thin waxed paper; second—a layer 2 of tin-foil, and, third, 5 a binder 3, which in practice will bear the name of the firm putting up the article or chewing-gum and any other advertising matter that may be desired. The layers of waxed paper and tin-foil are coequal in dimensions; but 10 the binder is considerably shorter than the wrapper proper, composed of the layers 1 and 2. At one side edge, as at 4, the binder projects beyond one longitudinal side edge of the waxed paper and tin-foil, and this projecting 15 portion is provided on its under side with adhesive material. During the wrapping of the package this adhesive margin or projecting edge after being properly moistened is cemented down upon the opposite longitudinal 20 edge portion of the binder for effectually securing the package. The parts being arranged as shown in Fig. 29, they are reversed in position—that is to say, they are turned upside down—so that the article of merchandise 25 or the block of chewing-gum is uppermost or lies above the wrapper, this taking place in the folding-box of the machine, as will hereinafter appear. As the wrapper and article are pushed into the folding-box the 30 longitudinal edge portions of the wrapper are forced upward into a perpendicular position, as shown in Fig. 30. One side of the wrapper is then pressed downward upon the article, as at 5, Fig. 31, and subsequently the 35 other side is folded down, as at 6, Fig. 32, and the adhesive margin 4 is pressed down, so as to cement the overlapping parts of the binder. After this has been effected end portions of the waxed paper and tin-foil are 40 folded downward, as at 7, Fig. 33, then the triangular portions 8, Fig. 33, are folded or tucked in laterally, as shown at 9, Fig. 34, and subsequently the remaining projecting end portions 10, Fig. 34, are folded upwardly 45 against the laterally-folded or tucked-in parts 9 and the downward-folded portions 7 to produce the complete package, Fig. 35, wherein the article or chewing-gum is effectually inclosed and protected from the effect of atmospheric influences. Inasmuch as the waxed paper is comparatively thin and the tin-foil lies outside of the same the upward folds 10 will tend to maintain their folded position; but it is possible under certain circumstances 50 to tuck these end portions 10 under the binder, although this is not considered essential and therefore is not shown and will not hereinafter be referred to.

It will be observed that in the completed 60 package the binder is only equal to the length of the article inclosed in the wrapper, and it is for this reason that the binder, as shown in Fig. 29, is of a length considerably less than the length of the layers of waxed paper and tin-foil, which, in fact, constitute the 65 wrapper proper.

Having described the method of folding the

wrapper to inclose the article of merchandise, I will now proceed to describe my improved machine, whereby the wrapping material is drawn or pulled longitudinally at regular intervals, wrappers or wrapper-sections are severed therefrom, the articles to be wrapped are placed in proper relation to the wrapper-sections, the wrappers and the articles are transferred to the folding mechanism, the folds are perfectly formed to produce the wrapped packages by mechanical means without hand manipulation, and the packages are lifted from the folding box or chamber and placed upon a suitable receiver or table, from whence they may be removed.

The articles of merchandise (indicated by the numerals 12, Figs. 3 and 6) which are to be inclosed within wrappers are stored in a vertical column or stack in a magazine composed of two perpendicular standards 13, (best seen in Figs. 1, 3, and 6,) constructed with channels, in which the ends of the articles lie and by which they are retained in a column or stack and are guided in a downward direction. The channeled standards may be of any desired height to receive and accommodate any quantity of articles which are to be inclosed within wrappers. The lower open ends of the standard are supported in any suitable manner—as, for example, by opposite side plates 14, Figs. 1 and 6, under which a slide-plate 15 (best seen in Fig. 20) is movable back and forth. The slide-plate 100 is provided at its front end with forwardly-projecting arms 16, having upturned flanges 17, the construction being such that when the slide-plate is moved rearward and the arms 16 lie directly under the lower open ends of the channeled magazine-standards a single article—as, for instance, a block of chewing-gum—will fall by gravity upon said arms and lie between the front edge of the slide-plate and the upturned flanges 17 of the arms 16, 110 while if the slide-plate be advanced or moved forward the article carried by the arms 16 will also be carried forward, and the solid portion of the slide-plate will move under the column or stack of articles and support the same until the article carried by the arms 16 is removed therefrom and the slide-plate is again moved rearward to place the arms directly under the lower open ends of the magazine-standards, whereupon the operation before 120 described will be repeated. The slide-plate moves back and forth directly above a table 18, Figs. 1 and 6, and at the right-hand side of this table is another table, as at 19, Figs. 2, 4, and 18, over which the wrapping material is moved longitudinally. In wrapping packages of chewing-gum the wrapping material is composed of webs, one of which is a simple paper binder, while the other is composed of waxed paper lying above tin-foil. It 130 is desirable that the tin-foil and waxed paper be compelled to move longitudinally in unison, and for this purpose I unite the waxed paper and the tin-foil by heat and pressure and

then wind this compound web upon a reel 20. The paper-binder web is wound upon a reel 21. It is possible, however, to wind the tin-foil and the waxed paper upon separate reels; but 5 where the waxed paper and tin-foil are united by heat and pressure and the compound web is wound upon a reel the tin-foil is strengthened to prevent tearing when pulled longitudinally, the waxed paper and foil must 10 move in unison, and their displacement relatively to one another is effectually prevented, whereby these parts of the wrapping material are susceptible of being practicably manipulated in the machine in a better manner 15 than if the waxed paper and foil were wound upon separate reels and simply superimposed without being actually connected or united by heat and pressure. The binder-web is of a width greater than the width of the web of 20 waxed paper and foil, so that one longitudinal edge of the binder-web will project laterally past one edge of the web of waxed paper and foil. This projecting edge is provided on its under side with adhesive, and therefore 25 in each completed wrapper produced, as will hereinafter appear, one side or edge portion of the binder 3, Fig. 29, will project and be supplied with adhesive, as described with reference to the part 4, Figs. 29 to 35, the 30 purpose of this being to cement or secure the package during the folding operation. At a point near the magazine and above the inner end of the table 19, which lies under the webs, are located two plates 22 and 23, having 35 notched leading edges, one plate being arranged directly above the other and slightly separated therefrom. The compound web of waxed paper and foil running from the reel 20 passes under the lowermost plate 23, while 40 the binder-web running from the reel 21 passes between the two plates 22 and 23, whereby the leading edges of the webs are slightly separated to enable the pairs of 45 nippers, hereinafter explained, to seize and pull the webs, one pair of nippers seizing the leading end of the compound web of waxed paper and tin-foil and the other pair of nippers seizing the leading end of the binder-web. The 50 compound web passes between elastic feed-rollers 24, 25, and 25^a, Fig. 2, geared together at their rear ends, as seen in Fig. 18, and designed to facilitate drawing a certain quantity of the compound web of waxed paper and foil from the reel 20 whenever the feed-rollers are rotated. The elastic feed-rollers 55 24 are mounted in a yoke-frame 24^a, pivoted at its inner end portion, as at 24^b, to fixed parts of the machine-frame, so that if the outer end of the yoke-frame be raised the 60 elastic feed-roller 24 will be elevated from contact with the feed-roller 25 for the purpose of introducing the webs of tin-foil and waxed paper, or, in other words, to facilitate threading the machine with these webs. The 65 binder-web passes between an elastic feed-roller 25^a and one of the rollers 24 and when rotated serves in a measure to advance the

binder-web longitudinally toward the nippers. These feed-rollers are simply for the purpose of drawing a quantity of the webs 70 from the reels and to facilitate the longitudinal drawing or pulling of the webs by the nippers above mentioned, the construction and operation of which will hereinafter be fully described in detail. 75

The feed-rollers 25 and 25^a are rotated at regular intervals to draw wrapping material from the reels by any suitable means; but I have illustrated and will hereinafter describe, in connection with the actuating and driving 80 devices of the machine, the particular rack-and-pinion mechanism represented for rotating the feed-rollers.

It is proper to here state that when the tin-foil and waxed paper are united by heat and 85 pressure to form a compound web, as hereinbefore stated, it is not essential to provide feed-rollers for drawing the tin-foil and waxed paper from the reel which carries the same, because the compound web possesses sufficient 90 strength to enable the reciprocating nippers to pull the web directly from the reel, and the same remarks apply to the binder-web, in that this is ordinarily composed of paper which is comparatively strong. Therefore, while I have shown and described the 95 feed-rollers and will hereinafter describe the means by which they are positively rotated at regular intervals, I do not limit myself to the use of these feed-rollers and their driving mechanism. 100

A cutter for severing a web into wrapper-sections is located directly at the left-hand side of the web flattening and guiding plates 22 and 23—that is to say, the cutter is located 105 at a point between the flattening and guiding plates and the magazine. The cutter is composed of two pivoted shear-blades 26 and 27, Figs. 4 and 17, operated at intervals, as hereinafter explained, so that when the leading 110 ends of the webs have been drawn longitudinally in front of the magazine a distance sufficient to provide the material necessary for a wrapper the shear-blades constituting the cutter instantly close and smoothly sever the 115 webs. As the webs are drawn longitudinally into a position in front of the magazine the slide-plate 15 at the lower end of the magazine is moved forward and an article lying on the arms 16 between the front edge of the 120 slide-plate and the upturned flanges 17 will be carried forward and placed beneath the wrapper-section, so that the wrapper actually lies above the article, and the article and 125 wrapper-section are in proper relation to be subsequently carried to the folding box or chamber 28, Figs. 1 and 6, through the medium of two gripping-jaws 29 and 30, (best seen in Figs. 6 and 22,) forming, respectively, fixed parts of yoke-frames 31 and 32. The 130 yoke-frame 32 of the gripping-jaw 30 is sleeved or loosely mounted upon a short longitudinal shaft 33, arranged in suitable bearings in parallel plates 34, running from front

to rear of the machine at or about the center thereof, one portion of this yoke-frame 32 being rigid with a pinion 35. The pinion 35, loosely mounted on one end portion of the shaft 33, forms a fixed part of the yoke-frame 32, loosely sleeved on the shaft at opposite extremities of the sleeve 36, which is fast to the shaft, as best seen in Fig. 22. The yoke-frame 31 of the jaw 29 forms part of the sleeve 36, fastened to the shaft 33, which latter is provided at one end, at a point outside of the left-hand side plate 34, with an attached pinion 37. The pinion 35 of the yoke-frame 32 engages a segmental rack 38 at the inner side 15 of the right-hand side plate 34, while the pinion 37, which is secured to the shaft 33, on which the sleeve 36 is mounted, engages a segmental rack 39 at the outer side of the left-hand plate 34. The segmental racks are independently operated, as will be hereinafter explained, and they swing back and forth in a direction from front to rear of the machine. In what may be called the "normal" position of the gripping-jaws 29 and 30 (indicated by 20 full lines in Fig. 6) the jaw 29 lies substantially flush with the inner end of the table 18, which is under the magazine, and therefore, when an article is discharged from the magazine, as the wrapping material is drawn longitudinally into a position in front of the magazine 25 the article is pushed under the wrapping material and is placed directly over the gripping-jaw 29. During this time the gripping-jaw 30, which is a part of the yoke-frame 32, lies in the folding-box, and after the wrapper-section and the article are in correct position above the jaw 29 the yoke-frame 32 is swung in the arc of a circle and its jaw 30 leaves the folding-box and coöperates with the jaw 29 to firmly grip and hold the article and the wrapper-section, after which the two jaws gripping the article and the wrapper-section swing forward in unison in the arc of a circle, and the jaw 30 enters the folding-box 28, so 30 that the article and the wrapper are reversed in their positions, and the article will lie above the wrapper-section instead of under the same, as when it was first gripped by the two jaws. The jaw 29 will then move back independent of the jaw 30 to the position shown in full lines, Fig. 6.

The front wall 40, Fig. 6, of the folding-box is fixed or immovable, while the rear wall is composed of a clamp-jaw 41, Figs. 6, 7, 8, 55 and 11, having a tailpiece 42 lying at the bottom of the box in such manner that when the article and the wrapper are deposited in the folding-box by the transferring and gripping jaws above referred to pressure is applied by the jaw 30 upon the tailpiece 42, the longitudinal sides of the wrapper are turned upward, and the clamp-jaw is caused to firmly grip the opposite longitudinal sides of the article to press the wrapper tightly against the side edges of the article and to firmly hold the article and the wrapper in fixed relation in the folding-box. By the means de-

scribed the article and the wrapper are under perfect control of mechanical parts of the machine and are absolutely prevented from displacement relatively to each other from the time they are seized by the gripping and transferring jaws and transferred to the folding-box until the entire folding operation is completed. The complete folding of the 75 wrapper by mechanical means will be described later on.

The plate forming the gripping-jaw 30, or the yoke-frame of this jaw, is constructed with an opening or recess to receive the 80 clamp-jaw 41 when the gripping-jaw is lowered into the folding-box, as best seen in Fig. 1, and the plate forming the gripping-jaw 29 is of such length that when the magazine slide-plate 15 is advanced its arms 16, with their upturned flanges 17, pass at opposite ends of the jaw 29, so that when the two gripping-jaws are closed together and are swung forward they raise the article from the arms and transfer the same, with the wrapper, to the folding-point.

I will now proceed to describe the nipper mechanism by which the webs of wrapping material are drawn or pulled longitudinally into a position in front of the magazine and over the article to be wrapped. There are two pairs of nippers, composed of fixed jaws 43 and movable jaws 44 and 44^a. (Best seen in Fig. 21.) The fixed jaws are carried by the inner ends of horizontally-movable slides 45, 95 and to the inner end portion of one slide the nipper-jaw 44 is pivoted, as at 46, and is articulated at one side of its pivot to one extremity of a lever 47. The movable jaw 44^a of the other nippers may form a rigid part of 100 a lever 47^a, pivoted as at 46^a. The reason for the differences in the construction of the two nipper-jaws is that the nipper-jaw 44 closes upwardly against a fixed jaw, while the nipper-jaw 44^a closes downwardly against a fixed 105 jaw. The outer ends of the levers 47 and 47^a are provided with roller-studs, as at 48, adapted to travel in longitudinal guideways 49 in the opposite sides of a bar 50, which is pivoted at its outer end, as 51, to a fixed part 52 110 of the machine-frame. The slides 45 are dovetailed to opposite sides of a fixed plate 53, 115 forming an extension of the machine-frame, and these slides are pivotally connected by links, as at 54, with the upper ends of vibrating levers 55, which at their lower ends are mounted on a fixed stud 56 in such manner that when the levers are vibrated the slides 45 are reciprocated, and consequently the nipper-jaws are correspondingly reciprocated. 120 The bar 50 is adapted to be raised and lowered by a vertical rod 57, connected therewith at its upper end, as at 58, Fig. 2, so that if the bar 50 be raised by elevating the rod 57 the levers 47 and 47^a will be so actuated as to 125 close the pivoted nipper-jaws 44 and 44^a for the purpose of gripping the leading edges of the webs of wrapping material, and, conversely, if the bar 50 be lowered the levers 47

and 47^a will cause the pivoted nipper-jaws to open and release the leading ends of the webs. The cams and connections for operating the vibrating levers 55 and the vertical rod 57 at timed intervals will be hereinafter explained in the description pertaining to the cam-shafts and driving devices of the machine, for which reason it is unnecessary to here explain the same.

10 In Fig. 2 the leading ends of the webs of wrapping material are indicated by the numerals 59 and 60, the web 59 being the binder-web and the web 60 the compound web of waxed paper and tin-foil. When the slides 45 are advanced, the bar 50 is depressed and the nippers are opened to seize and grip the leading ends of the webs, one pair of nippers being arranged to seize the binder-web 59 and the other pair to seize the compound web 60.

15 When the nippers are in position to grip the ends of the webs, the bar 50 is raised and the pivoted nipper-jaws 44 and 44^a are closed against the fixed jaws 43, after which the slides 45, by their connection with the vibrating levers 55, are retracted or commence to move outwardly, thereby drawing or pulling the webs between the web flattening and guiding plates 22 and 23 into a position in front of the magazine and over the gripping-jaw 29, Fig. 6, which at this time is flush with the table 18. As the webs are drawn longitudinally in front of the magazine an article is discharged therefrom and placed over the jaw 29 under the wrapping material, as before explained. When the requisite quantity of wrapping material has been drawn by the nippers into a position in front of the magazine, there is a pause in the longitudinal motion of the nippers, and at this instant the shear-blades 26 and 27 close and sever the webs to produce a wrapper. Immediately thereafter the nippers again move a limited extent in an outward direction to adjust the waxed paper and tin-foil into correct position, and then there is a pause in the motion of the pair of nippers which seizes the waxed paper and tin-foil, while the other pair of nippers, which seizes the binder part of the wrapper, continue their outward motion and adjust the binder into such position that the waxed-paper and tin-foil parts of the wrapper will project from opposite ends thereof, or, in other words, the binder will be shifted and placed in the position represented in Fig. 29, so that the end portions of the waxed paper and foil can be folded by the folding mechanism, hereinafter explained, without folding the end portions of the binder. When the two pairs of nippers seize the leading ends of the webs of wrapping material and commence their outward strokes, that pair of nippers which seizes the waxed paper and foil move slightly faster at the beginning than the pair of nippers which seizes the binder, so that the web of waxed paper and foil is drawn considerably ahead of the binder for the purpose of obtaining a wrapper in which the waxed pa-

per and foil are of a greater length than the binder. In other words, as the nippers recede and pull the webs longitudinally the 70 nippers which grip the waxed paper and tin-foil move ahead or slightly faster than the nippers which grip the binder-web until the requisite quantity of wrapping material is drawn longitudinally, whereupon there is a 75 pause in the longitudinal motion of both pairs of nippers and the quick-acting shear-blades sever the webs, after which the two pairs of nippers continue their receding motion; but the pair of nippers which grip the binder-web 80 moves ahead or slightly faster than the nippers which grip the waxed paper and foil, whereby the binder is shifted on the waxed paper and foil and placed in such position relatively thereto that the waxed paper and 85 foil extend from opposite ends of the binder to provide the material necessary to be folded in at the ends of the article, while the binder itself is not folded in at the ends, but is exactly or approximately the length of the completed 90 package. When the wrapper is severed from the webs by the shear-blades, the edges of the binder and the waxed paper and foil at the point where cut are exactly coincident, and therefore it is necessary to adjust the 95 binder-section longitudinally to place the same in correct position so that the waxed paper and foil will project beyond the binder at the ends of the wrapper. This is accomplished by the continued motion of the pair 100 of nippers which grip the binder after the other pair of nippers, which grip the waxed paper and foil, have adjusted the latter and cease their longitudinal motion. This will be best understood by reference to Figs. 2^a 105 and 2^b.

In Fig. 2^a the shear-blades 26 and 27 have just severed the webs to produce a wrapper. It will be seen that one pair of nippers has drawn the waxed-paper and foil web slightly 110 beyond the binder. The two pairs of nippers then shift the wrapper centrally over the gripping-jaw 29, Fig. 2^b, which is the jaw over which the article is placed by the discharging-slide at the bottom of the magazine.

In Fig. 2^b the article is represented as lying on the jaw 29, the wrapper is located above the article, one pair of nippers has placed the waxed paper and foil in correct position relatively to the article, the other pair of nippers has adjusted or shifted the binder part of the wrapper centrally over the waxed paper and foil, the shear-blades are open, and the gripping-jaw 30 is approaching the jaw 29 for the purpose of gripping the 125 wrapper and the article between the two jaws and transferring them to the folding-box.

As before stated, the binder-web is wider than the compound web of waxed paper and foil to provide a projecting margin at one side, which is provided with adhesive to cement or secure the wrapped package. This adhesive margin requires to be moistened, so that it can be subsequently pressed down and se-

cured. The moistening of the adhesive margin of the binder-web is effected as the web travels toward the shear-blades by which the webs are severed into wrappers through the medium of a rotary moistening-disk 61, Fig. 2, which is supplied with moistening liquid from a tank 62, Fig. 2, by disks 63 and 64, the latter dipping in the water in the tank and supplying the liquid to the disk 63, which in turn supplies the moistening-disk 61. The disk 61 projects up through the table 19, as best seen in Fig. 17, and the adhesive margin of the binder-web bears against the disk as the web is drawn or pulled longitudinally by the nippers. The disks 61, 63, and 64 are mounted on shafts having pinions 65, 66, and 67 at one end, which engage each other and are positively driven by a pinion 68, meshing with the pinion 67 and driven by a gear-wheel 69, the latter being rotated, as will herein-after appear.

After the nippers have drawn the webs longitudinally in front of the magazine and the wrapper has been severed therefrom by the shear-blades of the cutter and until the nippers again advance and seize the webs the latter should be held or pressed down in a fixed position upon the supporting-table 19 for the purpose of maintaining their leading ends in accurate position to be seized by the nippers. This is effected through the medium of a pressing-finger 70, Figs. 1, 2, 4, and 18, extending over the webs and secured at its rear end to a longitudinal rock-shaft 71, which at proper timed intervals is positively turned by means hereinafter explained to raise and lower the finger in such manner that when the finger is lowered it will press upon and hold the webs and when it is raised it will release the webs and permit them to be moved longitudinally by the nippers; and, further, the reel 20, carrying the roll of tin-foil and waxed paper, should be arrested in its rotation and held steady after the reel has turned sufficiently to supply the wrapping material necessary for a wrapper, as otherwise the momentum of the wheel might unwind an undue quantity of the tin-foil and waxed paper, which would sag down and be more or less in the way, and therefore objectionable. To arrest the reel at timed intervals for the purpose above stated, I provide the rock-shaft 71 with a brake, which, as here shown, is in the form of an arm 72. (Best seen in Fig. 18.) The brake-arm 72 and the pressing-finger 70 move in unison with the rock-shaft 71, so that when the brake-arm is caused to press against one end of the reel carrying the tin-foil and waxed paper the pressing-finger 70 is caused to press down upon the webs and firmly hold the same.

It is proper at this point to generally describe the folding devices, and therefore I will proceed to set forth their construction and operation, but will later on explain the mechanical devices by which all the folders are positively actuated. The folding-box is

of the same dimensions, substantially, as the dimensions of the article which is to be wrapped, and this folding-box is composed of the fixed front wall 40, Fig. 6, the pivoted clamp-jaw 41, upwardly and downwardly swinging end-folder wings 73, and oscillatory lateral tuckers or side-angle folders 74, located at the four corners of the box or chamber. The lateral tuckers or side-angle folders are approximately hemispherical in form or shape and have beveled portions 74^a, as best seen in Fig. 10. The wall 40 and the clamp-jaw 41 serve to turn the opposite longitudinal side portions of a wrapper to the perpendicular position shown in Fig. 30, when the article and the wrapper are reversed and pushed into the box by the gripping and transferring jaws 29 and 30. The end-folder wings 73 serve to fold upwardly end portions of the wrapper after other end portions have been folded downwardly and the tuckers or side-angle folders have tucked or folded in the angle portions 8, Fig. 33. The longitudinal side portions of the wrapper extending above the article, as shown in Fig. 30, are folded down and lapped one over the other through the medium of front and rear longitudinal folders, composed, as here shown, of thin flattened slide-plates 75 and 76. When the article and wrapper have been inserted into the folding box or chamber and as the gripping-jaw 29 leaves the same the front longitudinal folder-plate 75 moves rearward and folds down one longitudinal edge portion of the wrapper upon the article, and immediately following this the rear longitudinal folder-plate 76 moves forward and folds the other longitudinal side portion of the wrapper, which is provided with the projecting adhesive margin 4, Figs. 29, 30, and 31, down upon the other longitudinal fold. As this occurs the front folder-plate 75 moves slightly forward, so that there is a space provided between the adjacent edges of the two longitudinal folder-plates, which space is approximately coextensive with the adhesive margin of the binder part of the wrapper. It is now essential to first form the downfolds 7, Fig. 33, at the end portions of the tin-foil and waxed-paper parts of the wrapper. To accomplish this, I provide an arm 77, Figs. 1, 2, 3, 4, 7, and 12, constructed to swing in a perpendicular plane and supported at one end through the medium of a stud-shaft 78, rigidly mounted in a fixed bearing 79. This arm is hollow to form cheek-pieces 77^a and 77^b, Figs. 7 and 12, and carries two folder and gripper wings 80 and 81, arranged a distance apart substantially coequal with the length of the article to be wrapped. The folder and gripper wings are pivoted upon small axles or shafts 82 and 83, Fig. 12, and they are opened and closed at timed intervals by the means hereinafter described. The arm 77 is provided between the folder and gripper wings 80 and 81 with a flexible or soft pressing-pad 84, so that when the arm is lowered by

the means which will hereinafter be fully explained the pad presses upon the adhesive margin of the binder part of the wrapper and effectually secures the same in position, it being understood that the adhesive on the said margin of the wrapper has been previously moistened by the moistening-disk 61. Concurrently with the pressure of the pad 84 on the adhesive margin referred to the folder 10 and gripper wings 80 and 81 swing to their closed position, thereby producing the down-folds 7, Fig. 33, which are the first folds formed at the ends of the wrapper. The instant the down folds are completed the folder-wings 80 15 and 81 of the arm 77 open or rise to an approximately horizontal plane to move them out of the way and permit the lateral tuckers or side-angle folders 74 to turn and form the lateral tucks or side-angle folds 9, Fig. 34. 20 The tuckers 74 then instantly resume their normal position, (represented in Figs. 1 and 8,) and the end-folder wings 73 of the folding-box rise and fold upward the remaining end portions of the wrapper to produce the completed package, Fig. 35. During this time the swinging arm 77 remains in its lowered position, and after the end-folder wings 73 are swung downward to their open position, in which position they are substantially horizontal, the folder and gripper wings 80 and 25 81 again close against the ends of the wrapped package and the arm swings in the arc of a circle to lift the package out of the folding-box, the longitudinal folders 75 and 76 first 30 moving out of the way to permit this removal of the package. The arm makes substantially a half-revolution and moves downward through a slot 85 in a receiving-table 86 to place the lower side of the wrapped package 35 level, or nearly so, with the upper surface of the table, whereupon a pusher 87, moved back and forth by means hereinafter explained, pushes the wrapped package off of the arm (the folder or gripper wings 80 and 81 having previously 40 released the package) onto the section 88 of the receiving-table, so that when subsequently another package is pushed off of the arm by the pusher 87 the first-mentioned package 45 will be delivered into a chute 89, which may 50 deposit the wrapped package in a box or upon a suitable carrier or otherwise dispose of the same, according to the conditions required.

It will be observed from the foregoing that parts of the arm 77 not only serve to secure the adhesive part of the binder, and thus seal the wrapped package, but that some of these parts—to wit, the wings 80 and 81—serve to produce the first downfolds of end portions of the wrapper and subsequently to seize and 55 lift the wrapped package out of the folding-box and to deposit it at a convenient point, from whence it may be carried or removed.

Referring to the end-folder wings 73 of the folding-box, it will be observed that they are 60 pivoted, as at 90, Fig. 11, to the ends of a bottom plate 91, recessed to receive the gripper-jaw 30. The folder-wings 73 are provided

with arms or tailpieces 92 and 93, the arm or tailpiece 92 being eccentrically connected by a link 94 with an oscillatory toothed disk 95, 70 Figs. 1, 7, and 8, while the arm or tailpiece 93 is eccentrically connected by a link 96 with said toothed disk 95. The toothed disk is mounted on a short axle or shaft 97, Fig. 7, and when the disk is turned in one direction 75 the end-folder wings 73 are closed or moved to a perpendicular position, and when the disk is turned in the opposite direction the end-folder wings are opened or moved to an approximately-horizontal position, as represented in Figs. 7 and 8. The toothed disk is 80 positively oscillated at timed intervals by means hereinafter explained.

Referring to the lifting-arm 77, with its folder and gripper jaws 80 and 81, Figs. 7 85 and 12, it is proper to here state that these jaws are provided with tailpieces 98 and 99, eccentrically connected by links 100 and 101 with a hub 102, Fig. 14, which is adapted to be positively turned on the shaft 78 at timed 90 intervals first in one direction and then in the other for the purpose of opening and closing the folder and gripper wings 80 and 81. The cheek-piece 77^a of the lifting-arm 77 is rigidly connected with a hub 103, having a 95 pinion 104, turned by the means hereinafter explained first in one direction and then in the other to swing the arm 77 in the arc of a circle. The other cheek-piece 77^b of the lifting-arm 77 is loose upon the hub 102, which hub is provided with a pinion 105 and is confined in place on the shaft 78 by a collar 106, said pinion 105 being also turned first in one direction and then in the other by the means 100 hereinafter described for operating the folder and gripper jaws 80 and 81 in the manner 105 above set forth.

I will now proceed to describe in detail the mechanical devices for positively actuating the various working parts hereinbefore set forth. This order of procedure in the description is pursued in that it is believed the construction and operation of the entire machine 110 will be more readily understood.

At the front of the machine-frame is arranged a longitudinal line-shaft 107, mounted in suitable bearings 108, Fig. 1, and provided at the left-hand end with a miter-gear 109, meshing into a miter-gear 110 on a transverse primary counter-shaft 112, having a 115 rigidly-attached gear-wheel 113 of comparatively-large diameter, driven by a pinion 114 on the inner end of a main drive-shaft 115, rotatable in a fixed sleeve-bearing 115^a. (Best 120 seen in Fig. 6.) This drive-shaft is provided at its outer end with a loosely-mounted pulley 116, designed to be driven by a belt connection with a power-shaft, but which can 125 obviously be operated manually, if desired. The drive-shaft is provided with a clutch-section 117, adapted to be operated by a suitable clutch-lever, not necessary to illustrate, so that it can be thrown into and out of engagement with a clutch-section on the pulley 130

to lock the latter to or unlock it from the drive-shaft, whereby the machine may be started and stopped as occasion demands.

The slide-plate 15, by which the articles are discharged at timed intervals from the magazine, is pivotally connected by a link 118^a or otherwise with the upper end of a vibratory lever 118, Figs. 4, 5, and 6, pivoted at its lower end, as at 119, to the base of the machine-frame. The vibratory lever is pivoted between its upper and lower ends to the rear end of a connecting-rod 120, which at its front ends is pivotally connected to a cam-actuated lever-arm 121, Figs. 3 and 6, having a roller-stud 122, engaging a cam-raceway in the left-hand side of a cam 123, Fig. 1, on the line-shaft. This cam is suitably constructed to actuate the lever 121 and advance the slide-plate 15 of the magazine as the web is drawn longitudinally in front of the magazine for the purpose of placing the article which is to be wrapped beneath the wrapping material and over the gripping-jaw 29, Figs. 2^b and 6. After the jaw 30 is lowered to seize the article and the wrapper and the article are raised from the arms 16 of the magazine slide-plate 15 the latter is given its back stroke by the cam 123 to place the arms 16 in a position directly beneath the channeled standards 13 of the magazine, whereupon another article will descend by gravity upon the arms and lie between the front edge of the slide-plate and the upturned flanges 17 of the arms.

The lower end of the lever-arm 121 is pivotally mounted upon a short horizontal axle or pintle 124 common to other lever-arms hereinafter mentioned and mounted in suitable bearings at the front of the base-frame of the machine.

As hereinbefore stated, the elastic feed-rollers 24, 25, and 25^a serve to draw or pull at intervals quantities of the webs of wrapping material from the reels. The intermittent action of the elastic feed-rollers may be effected by providing the front ends of the shafts 125 and 126 of the feed-rollers 25 and 25^a with pinions 127 and 128, (best seen in Figs. 15 and 16,) which are engaged at intervals by a duplex rack-bar 129, having at its right-hand end a toothless portion 130, which will not turn the pinions. The rack-bar is reciprocated at timed intervals by a vibratory lever-arm 131, pivotally connected at its upper end with the rack-bar through the medium of a link 132. The lower end of the lever-arm 131 is mounted on a fixed stud 133, Fig. 3, and it is vibrated through the medium of a connecting-rod 134, pivoted at its left-hand end to a vibrating lever-arm 135, mounted at its lower end on a fixed stud 136, Fig. 5. The lever-arm 135 is vibrated through the medium of a suitable cam-raceway in the right-hand side of a cam 137 on the counter-shaft 112, so that as the nippers advance to seize the leading ends of the webs the rack-bar is moved to the right, but does not turn the elastic feed-rollers 25 and 25^a in this movement,

since the pinions 127 and 128 are loose on the shafts 125 and 126. After the rack-bar has reached the limit of its right-hand stroke 70 and the nippers commence to recede to draw or pull the web between the guide-plates 22 and 23 the rack-bar acts upon the pinions and through the medium of any suitable pawl-and-ratchet devices the pinions will 75 turn the shafts 125 and 126, and thereby positively rotate the elastic feed-rollers 25 and 25^a in the direction required to draw or pull a quantity of the webs of wrapping material from the reels. As here shown, the pinions 80 127 and 128 are cut away at one side, as at 127^a and 128^a, and the rack-bar slides in these cut-away parts, so that when the toothless portion 130 of the rack-bar slides or lies in said cut-away parts the pinions cannot turn. 85 Inasmuch, however, as the pawl-and-ratchet devices for effecting the positive rotation of the shafts 125 and 126 in one direction to feed the material are well-known devices, I do not deem it necessary to describe the same in detail, particularly in view of the fact that if the webs of tin-foil and waxed paper are united by heat and pressure to form a compound web the elastic feed-rollers, the pinions, the rack-bar, and its actuating devices may be dispensed with, because the compound web of tin-foil and waxed paper, being united, possesses sufficient strength to be drawn or pulled longitudinally by the nippers alone without danger of the tin-foil tearing or becoming dis- 90 placed relatively to the waxed paper.

As before stated, when a sufficient quantity of the webs of wrapping material to form a wrapper has been drawn or pulled longitudinally in front of the magazine the webs are 105 severed by a cutter composed of two shear-blades 26 and 27, which are automatically opened and closed at timed intervals, as I will now explain.

The shear-blades are best seen in Figs. 4 110 and 17, and, as shown, both are pivotally mounted upon a common axis, as 138. The upper shear-blade 26 is constructed with a tailpiece 139, extending rearwardly and connected by a link 140 with one arm of a bell-crank lever 141, Fig. 19, fixed on a rock-shaft 142, arranged in a suitable bearing 143. The lower shear-blade 27 is connected by a link 144 with a crank-arm 145, fixed to the rock-shaft 142, the construction being such that 115 when the bell-crank lever 141 is vibrated or rocked the shear-blades are opened or closed. The upwardly-projecting arm of the bell-crank lever 141 is connected by a rod 146 with the upper end of a lever-arm 147, Fig. 19, pivoted at its lower end, as at 148, to the frame of the machine and having near its upper end a lateral roller-stud 149, designed to be acted upon by a cam 150 on the rear end of the counter-shaft 112. The lever-arm 147 carries 120 a trip-dog 151, pivoted intermediate its ends to the lever-arm and having one end provided with a hook, as at 152, and the other end upwardly curved to form a convex shoulder 153,

designed to be operated upon by a laterally-projecting trip-pin 154 on the rear face of the cam 150, as will hereinafter appear. The lever-arm 147 is drawn toward the cam 150 by 5 a suitable spring 155, connected at one end with the lever-arm and at the other end with a fixed plate 155^a, Fig. 5, or other device, and normally, as when the shear-blades are completely opened, the hook 152 of the trip-dog 10 151 engages and is held by a stop-lug 156 on a fixed plate 157. The hook is pressed downward into engagement with the stop-lug by a spring 158, carried by the lever-arm 147 and pressing upon the trip-dog. The periphery 15 of the cam 150 is constructed with a recessed or cut-away portion 159, so that during rotation of the cam when the lateral pin 154 acts upon the convex shoulder 153 of the trip-dog to raise the hook 152 thereof from engagement 20 with the stop-lug 156 the spring 155 will pull the lever-arm 147 to the left, and as the cut-away portion 159 of the cam will at this time register with the roller-stud 149 the latter can pass into the recessed or cut-away 25 portion of the cam, and the swinging action of the lever-arm 147 will pull the connecting-rod 146, swing the bell-crank lever 141, and turn the rock-shaft 142 in the direction necessary to raise the links 140 and 144, thereby 30 quickly close the shear-blades 26 and 27 to effect the cutting operation by which the webs are severed and a wrapper is produced. As the cam 150 continues to rotate the roller-stud 149 will ride upon the eccentric part of 35 the periphery thereof and force the lever-arm 147 in a direction away from the cam, so that the shear-blades are opened, the spring 155 is stretched, and the hook 152 of the trip-dog 151 is caused to again engage the stop-lug 40 156, thereby holding the shear-blades in their open position for a subsequent operation, as before set forth. The shear-blades can be more or less slowly opened, and when opened they are held in this position a sufficient 45 length of time for the folding operation to be completed and the webs drawn longitudinally in front of the magazine a distance sufficient to produce another wrapper.

The yoke-frames 31 and 32, which respectively carry the gripping and transferring jaws 29 and 30, by which the article and the wrapper are gripped and transferred from a point adjacent to the magazine to the folding-box, are operated at proper timed intervals 50 through the medium of devices which I will now describe. The segmental rack 39, Figs. 1 and 5, which engages the pinion 37, forms a part of an arm 160, pivoted at its lower end on a longitudinal shaft 161. The segmental rack 38, Fig. 1, which engages the pinion 35, forms a part of an arm 162, Fig. 5, also pivoted at its lower end on the shaft 161. The rack-arm 160 is connected by a link 163 with a vibratory arm 164, (best seen in Fig. 24,) 55 mounted at its lower end on the short horizontal shaft 124. The vibratory arm 164 engages a cam-raceway in the left-hand side of

a cam 165, mounted on the line-shaft 107. The rack-arm 162 is connected by a link 166 with a vibratory arm 167, pivoted at its lower 70

end on the short longitudinal shaft 124. The arm 167 has a part engaged with a cam-raceway in the right-hand side of the cam 123, as best seen in Fig. 26. The cam-raceways of the cams 123 and 165 are of such suitable construction that during the rotation of these cams the rack-arms 160 and 162 will be moved back and forth for rotating the pinions 35 and 37, as I will now set forth.

Assuming that the gripping and transferring jaw 30 lies in the folding-box, as in Figs. 1 and 6, and the jaw 29 is in proximity to the table 18 to receive an article pushed from the magazine by the slide-plate 15 and the main drive-shaft is operated to turn the counter-shaft, and thereby correspondingly turn the front line-shaft, and also assuming that the webs have been drawn longitudinally over an article placed over the jaw 29, the rack-arm 162 will be drawn forward by the action of the 80 cam-raceway in the right-hand side of the cam 123 on the lever-arm 167, thereby turning the pinion 35 in the direction necessary to swing the yoke-frame 32 away from the folding-box and rearward to cause its jaw 30 to co-operate with the jaw 29 to grip and hold the article and the wrapper. After this occurs the two rack-arms 160 and 162 will be moved in unison toward the rear of the machine, and consequently both pinions 35 and 90 37 will be rotated in unison in the direction required to swing both gripping-jaws forward while holding the article and the wrapper and cause the jaw 30 to enter the folding-box 95 28. The rack-arm 160 will then remain stationary, but the cam-raceway in the left-hand side of the cam 165 will act upon the vibratory arm 164, which is connected with the rack-arm 160, and swing the same forward, while the rack-arm 162 remains motionless in 100 its rear position. Consequently the gripping and transferring jaw 29 will be swung rearward independent of the jaw 30 and placed in proper relation to the table 18, while the gripping-jaw 30 remains in the folding-box 105 110 until after the completion of the folding operation. During the folding operation and while the nippers are advanced and retracted to draw or pull the webs longitudinally in front of the magazine both rack-arms 160 and 162 remain motionless. The same order of procedure occurs for each package which is wrapped. The gripping of the article and wrapper and their transfer by the gripping-jaws while held in fixed relation to one another from a point near the magazine to the folding-box near the front of the machine effectually prevent displacement of the article and wrapper relatively to one another, and therefore all packages will be correctly 115 120 125 wrapped alike.

The vibratory levers 55, by which the slides 45 of the nipper mechanism are reciprocated, are actuated in the following manner: One of

the levers 55—that is to say, the front one—is connected by a link 168, Figs. 1 and 3, with the vibratory lever-arm 135, which is actuated by the cam-raceway in the front side of 5 the cam 137, as before stated. The other lever-arm 55—that is to say, the rear one—is connected by a link 169, Fig. 2, with a lever-arm 170, mounted at its lower end on the stud or shaft 136, on which the lever-arm 135 is 10 mounted. The lever-arm 170 carries a roller-stud engaged with a cam-raceway in the rear face of the cam 137, and the raceways in this cam are of suitable construction to produce the particular motions of the nippers herein- 15 before explained. During the time the gripping and transferring jaws 29 and 30 are moving the slide-bars 45 and the nippers remain motionless, except that as the jaw 29 approaches the table 18 the rear lever-arm 170 is 20 acted upon by the cam-raceway in the rearface of the cam 137, so that the rear slide-bar 45 commences to advance and places its nippers in alinement with or in correct position relatively to the nippers of the front slide-bar 45. 25 Both slide-bars then advance in unison, and as they approach the leading ends of the webs the pivoted bar 50 is lowered for the purpose of opening the nipper-jaws. The bar 50 is connected at the end portion opposite its pivoted 30 end with the upper extremity of the vertical rod 57, which is preferably adjustable through the medium of a turnbuckle and pivotally connected at its lower extremity with a crank-arm 171, fixed to one end of a rock-shaft 172, 35 Fig. 2. The other end of the rock-shaft is provided with a lever-arm 173, having a roller-stud 174 engaging a cam-raceway in the front face of a cam 175, mounted on the counter-shaft 112. The cam-raceway in the front face 40 of the cam 175 is so constructed that at timed intervals the lever 173 will be actuated to rock the shaft 172, and thereby pull the bar 50 downward, while at other times the parts will be operated to raise the bar 50, and thereby 45 close the nipper-jaws. The nipper-jaws are closed immediately after they pass into position to seize the leading edges of the webs of wrapping material, at which instant the bar 50 is raised, thus closing the nipper-jaws. 50 When this occurs, the cam-raceways in the front and rear sides of the cam 137 commence to act upon the lever-arms 135 and 170 to move them toward the left-hand end of the machine, thereby correspondingly swinging 55 the vibratory arms 55 and imparting the re-tracting motion to the bars 45, so that the webs are drawn longitudinally in front of the magazine and over an article previously placed over the gripping-jaw 29. As the nippers are 60 retracted the rear slide-bar, carrying the nippers which grip the tin-foil and waxed-paper webs, moves slightly faster than the front slide-bar, carrying the nippers which grip the binder-web, for the purpose of drawing the 65 leading end of the tin-foil and waxed paper considerably beyond the leading edge of the binder-web. In this action of the nippers

they pull the foil and waxed paper longitudinally between the feed-rollers regardless of the bite of these rollers, which, however, is 70 comparatively slight. The pulling of the foil and waxed paper between the feed-rollers is facilitated by mounting the rollers 24 in the pivoted yoke-frame 24^a, Fig. 2, as before explained. After the requisite quantity of the 75 webs has been drawn in front of the magazine the shear-blades instantly sever the webs to produce the material for a wrapper, during which time there is a pause in the longitudinal motion of both pairs of nippers to afford 80 time for the cutting action of the shear-blades. Subsequently the front slide-bar 45, carrying the nipper-jaws which grip the binder, is further retracted, and the binder is thus 85 shifted along until it is centrally placed relatively to the waxed paper and tin-foil in such manner that the latter projects at opposite ends beyond the ends of the binder part of the wrapper. The gripping and transferring jaw 30 now moves out of the folding-box onto 90 the wrapper and article, and they are gripped by the two jaws 29 and 30, as before explained. The nippers are then further retracted to move them out of the path of the end of the 95 tin-foil and waxed-paper wrapper, whereupon the gripping and transferring jaws swing forward and place the article in the folding-box, as I have hereinbefore fully explained. 100 As hereinbefore stated, one longitudinal edge of the binder-web projects past or in front of the webs of tin-foil and waxed paper, and such projecting edge is provided with adhesive moistened by the moistening-disk 61. The moistening-disk 61 and the supply-disks 63 and 64, by which the liquid or water is 105 transferred from the tank 62 to the moistening-disk, are geared together at one end by the pinions 65, 66, and 67, Fig. 4, the latter pinion engaging a pinion 68, driven by a comparatively large gear-wheel 69, which is mounted 110 on the rear end of a secondary counter-shaft 176. The front end of this secondary counter-shaft is geared to the front line-shaft by bevel-gears 177 and 178, the latter having a cam or eccentric projection 179 constructed to act 115 upon the front end of a lever-arm 180, which at its rear end forms a part of a sleeve 181, mounted on a pivot-pin 182, as best seen in Figs. 4 and 28. The sleeve 181 is provided with a rearwardly-projecting crank-arm 183, 120 pivoted to the lower end of a connecting-rod 184, which at its upper end is pivoted to a frame or support 185, in which the shafts of the disks 61 and 63 are mounted. The frame or support 185 is pivotally mounted at the 125 right-hand end of the machine on the shaft of the disk 64, so that the opposite end of the frame or support in which the shaft of the moistening-disk 61 is arranged can be raised and lowered in such manner that at certain 130 times the moistening-disk 61 will be pressed more or less tightly against the adhesive margin of the binder-web and at other times the moistening-disk will be lowered out of con-

tact with the adhesive margin. The end of the frame or support 185 which carries the moistening-disk 61 is raised by the action of the cam or eccentric projection 179 on one side of the bevel-gear 178 acting upon the front end of the lever-arm 180, thereby raising the crank-arm 183, and correspondingly raising the frame or support 185 to press the moistening-disk against the adhesive margin 10 of the binder-web. This occurs after the nippers have been advanced and seize the leading ends of the webs to draw or pull them longitudinally in front of the magazine. When this motion of the web is effected and as the shear-blades close to sever the webs, the cam or eccentric projection 179 ceases its downward pressure upon the front end of the lever-arm 180 and a spring 186 pulls the crank-arm 183 downward, and thereby lowers the frame or support 185 to remove the moistening-disk from contact with the adhesive margin of the binder-web.

I have previously explained that the webs of wrapping material are held down by a pressing-finger 70 upon the table 19 to maintain their leading ends in accurate position to be seized by the nippers and to prevent possible longitudinal motion of the webs a greater or less extent. The rock-shaft 71, to which the pressing-finger is secured, is provided with a pendent crank-arm 187, Fig. 18, pivoted to the rear end of a connecting-rod 188, which at its front end is pivoted to a vibratory arm 189, Figs. 3 and 27, mounted at its lower end on a fixed stud 190. This vibratory arm carries a roller-stud 191, engaging a cam-raceway in the left-hand side of a cam 192 on the line-shaft, by which the vibratory arm is moved back and forth at timed intervals to rock the shaft 71, and thereby lower and raise the pressing-finger 70. The rock-shaft 71 also carries the brake-arm 72, Fig. 18, for the reel 20, on which the webs of tin-foil and waxed paper are wound in such manner that when the pressing-finger is lowered to hold the leading ends of the webs stationary the brake-arm is thrown into contact with one end of the reel 20 and the latter is arrested in its motion, thus preventing the reel unwinding an undue quantity of the tin-foil and waxed paper which might occur, due to the momentum of the reel. When the pressing-finger 70 is raised to release the leading ends of the webs, the brake-arm is removed from contact with the reel 20, and the latter can then rotate for unwinding the required quantity of tin-foil and waxed paper therefrom.

Referring back now to the folding-box containing the oscillatory tuckers or side-angle folders 74 and the end-folder wings 73 actuated by links 96, eccentrically connected with the toothed disk 95, I will set forth the devices whereby the tuckers or side-angle folders 74 and the toothed disk 95 are positively operated.

The toothed disk 95 engages a rack 193,

Figs. 1, 3, 5, and 23, which, as here shown, is segmental in shape and forms part of one arm 194 of a bell-crank lever sleeved at its angle upon a stud 195, extending laterally from one of the side plates 34. The sleeved part of the bell-crank lever is connected with one end of a spring 196, Fig. 5, which normally tends to turn the bell-crank lever in the direction necessary to raise the segmental rack 193, thereby turning the toothed disk 95 in such manner as to open the end-folding wings 73 and cause them to lie substantially horizontal. The other arm 197 of the bell-crank lever is provided near its lower end with a lateral lug 198, normally engaged by a hooked arm 199 of a trip-dog 200, having the form of a bell-crank lever. This trip-dog is pivoted at its angle to the upper end of a vibratory lever-arm 201, mounted at its lower end on the short horizontal shaft 124 at the front of the machine. The other arm 202 of the trip-dog extends downward to such extent that it will at a certain time strike the front line-shaft 107 to trip the trip-dog and disengage its hooked arm 199 from the lug 198. The vibratory lever-arm 201 is provided with a roller-stud 203, engaging a cam-raceway in the right-hand side of a cam 204 on the line-shaft 107, the construction being such that as the nippers are advancing to seize the leading ends of the webs of wrapping material the lever-arm 201 is swung forward by the cam-raceway in the side of the cam 204, thereby carrying forward the trip-dog 200 and causing the hooked arm 199 thereof to act on the lug 198 and pull the arm 197 forward to lower the segmental rack 193 and turn the toothed disk 95 in the direction necessary to close the end-folder wings 73, or rather move them to a perpendicular position, to complete the folding of the package after the longitudinal folders 75 and 76 have acted, the pressing and lifting arm 77 has formed the downward folds 7, and the oscillatory tuckers 74 have formed the end tucks or side-angle folds. When the vibratory arm 201 is carried forward such a distance that the lower end of the pendent arm 202 of the trip-dog 200 strikes the line-shaft 107, the hooked arm 199 will be raised out of engagement with the lug 198 and instantly the retractile power of the spring 196 will swing the arm 197 rearward and raise the segmental rack 193, thus turning the toothed disk 95 in the direction necessary to open the end-folder wings 73 or throw them down to a substantially horizontal position. The continued rotation of the cam 204 will move the vibratory lever-arm 201 rearward, and the hooked arm 199 will again be engaged with the lateral lug 198 for a subsequent operation.

At this time—that is to say, when the hooked arm 199 is made to engage the lateral lug 198—the vibratory lever-arm 201 will stand motionless, due to the construction of the cam-raceway in the cam 204, which engages the lever-arm. This lever-arm remains motionless until the article and

wrapper are transferred from a point directly in front of the magazine to the folding-box, the longitudinal folders have acted, the swinging, pressing, and lifting arm has descended 5 and formed the downfolds at the ends of the wrapper, and the oscillatory tuckers have formed the end tucks or side-angle folds and resumed their normal position. At this instant the nippers are advancing and the vibratory lever-arm 201 is moved forward, thereby causing the segmental rack 193 to descend at the required time and turn the toothed disk 95 in the proper direction to close or raise the end-folder wings 73, by which the folding of 15 the ends of the wrapper is completed.

The oscillatory tuckers or side-angle folders 74 are positively operated, as I will now explain. These tuckers or folders are mounted on perpendicular spindles 205 and 206. (Best 20 seen in Figs. 7, 9, and 10.) The lower ends of the spindles 205 are provided with pinions 207, engaging racks 208 at opposite edges of a horizontally-slidable plate 209. The lower ends of the spindle 206 are provided with mutilated pinions 210, engaged with the pinions 207, but not engaging the racks 208, the purpose of this being that when the plate 209 is moved in one direction its racks 208 will turn the pinions 207 and the latter will turn the 25 mutilated pinions 210, whereby the beveled parts 74^a of the tuckers or side-angle folders at the ends of the folding-box will be turned inwardly for the purpose of forming the tucked-in parts or the side-angle folds of the wrapper. 30 A reverse motion of the plate 209 will open the tuckers or side-angle folders, so that they will normally stand in the position represented in Figs. 1 and 8. The plate 209 is longitudinally slotted, as at 211, Fig. 9, and the edges 35 of this slot engage a guiding or supporting plate 212, Fig. 7, screwed to the center of a bottom plate 213, through which the lower ends of the spindles 205 and 206 project, so that the pinions 207 and 210 and the slide- 40 plate 209 lie below said bottom plate 213. The slide-plate 209 is connected to the upper extremity of a vibratory lever-arm 214, mounted at its lower end on the short shaft 124, as best seen in Figs. 6 and 25, and provided with 45 a roller-stud 215, acted upon by a suitable cam 216 on the line-shaft in such manner that after the folder-wings of the pressing and lifting arm 77 have formed the downfolds at the ends of the wrapper and have resumed their normal 50 position the slide-plate 209 will be drawn forward or in a direction toward the line-shaft 107, thereby turning the tuckers or side-angle folders 74 in the direction necessary to form the tucks or side angles at the ends of 55 the wrapper. The instant the slide-plate 209 reaches the limit of its forward stroke it is moved rearward by the cam 216 and lever-arm 214, and the tuckers or side-angle folders are turned to normal position, so that the 60 end-folders 73 of the folding-box can be closed or swung upward to complete the final folds in the wrapper. While these final folds are

being formed the slide-plate 209 remains motionless, and consequently the oscillatory tuckers or side-angle folders remain motionless until the proper time arrives for a subsequent operation. 70

The first folds formed in the wrapper are the longitudinal folds, which is accomplished through the medium of the horizontally-slid- 75 ing folder-plates 75 and 76, which are positively operated, as I will now set forth. The front longitudinal folder-plate 75 is movable back and forth in suitable guides 217, Figs. 1, 3, and 6, and it is connected at its upper side 80 with the upwardly-projecting arm 218, Fig. 6, of a bell-crank lever 219 through the medium of a link 220. The angle of the bell-crank lever is sleeved to a fixed stud 221, and its other arm 222 extends downwardly and is provided with a roller-stud 223, engaging a suitable cam-raceway in the right-hand side of the cam 165, Figs. 6 and 24, the construction being such that as the gripping and transferring jaw 29 rises out of the folding-box and 85 the pressing and lifting arm 77 commences to swing toward said folding-box the longitudinal folder-slide 75 moves rearward and folds down one longitudinal side portion of the wrapper. The rear longitudinal folder-slide 90 95 209 (best seen in Figs. 1 and 6) is then moved forward by the following means: The folder-slide 76 is connected with but elevated considerably above a horizontal slidable base-plate 224, so that this folder-slide lies sub- 100 stantially level with the top of the folding- box. The under side of the base-plate 224 is pivotally connected by a link 225 with the upper end of a vibratory lever-arm 226, Figs. 6 and 25, pivotally mounted at its lower end 105 on the short shaft 124 and provided with a roller-stud 227, engaging a suitable cam-race- way in the right-hand side of a cam 228, mounted on the line-shaft 107. As the rear longitudinal folder-plate 76 moves forward it 110 folds down the other longitudinal side portion of the wrapper, which side portion is pro- 115 vided with the projecting adhesive margin of the binder. The front longitudinal folder- slide 75 then moves forward a slight extent, 120 so that the adjacent edges of the two longi- 125 tudinal folder-slides are separated to permit the pad 84 of the pressing and lifting arm 77 to press upon the adhesive margin of the binder and cause it to be firmly secured. 130 At the instant this occurs the folder-wings 80 and 81 of the pressing and lifting arm close to form the downfolds 7 at the ends of 125 the wrapper and then quickly open or resume their normal position, which is substantially horizontal, to permit the operation of the tuckers or side-angle folders 74 and end-folder wings 73, as hereinbefore explained.

The pinions 104 and 105 are positively op- 130 erated to swing the pressing and lifting arm 77 and actuate its folder-wings 80 and 81 at the proper times in the following manner: These pinions respectively engage two per- 135 pendicular slidable rack-bars 229 and 230,

guided in their movements by a vertical plate 231, Fig. 12, screwed to a standard 232, forming a part of the main frame of the machine. The rack-bar 229 is pivotally connected by a link 233 with one arm 234 of a bell-crank lever, Figs. 4^a and 13, having its angle sleeved upon a fixed stud 235 and its other arm 236 carrying a roller-stud 237, engaging a cam-raceway in the right-hand face of a cam 238, 5 mounted on the front line-shaft 107, whereby the rack-bar 229 will be positively raised and lowered at the proper intervals to swing the arm 77 in the arc of a circle to and from the folding-box, it being understood that the rack-bar 229 engages the pinion 104, having the hub 103, to which the cheek-piece 77^a of the arm is rigidly attached, so that whenever the pinion 104 is turned the arm 77 is swung in 10 a circular path.

10 The rack-bar 230 serves to open and close the folder-wings 80 and 81 of the pressing and lifting arm 77 at predetermined intervals. The two rack-bars are connected by a link 239, pivoted intermediate its ends upon a stud 240, projecting from the rack-bar 229. This link extends at one end, as at 241, and this extension is connected with one end of a spring 242, having its other end engaged with a pin 243, fixed to the rack-bar 229. The 15 other end of the connecting-link 239 is provided with a slot 244, through which passes a pin 245 on the rack-bar 230. The extension 241 of the link lies in the path of a fixed abutment 246, Figs. 4 and 13, so that when 20 the two rack-bars ascend the extension will strike the abutment for a purpose which will hereinafter appear.

25 Assuming that the pressing and lifting arm 77 lies approximately horizontal in the slot 85 of the receiving-table 86 and that an article and a wrapper are being transferred by the gripping and transferring jaws 29 and 30 from the magazine discharge-slide to the folding-box, the two rack-bars will be in their 30 highest position, as shown in Fig. 13, and the link 239 will lie in an incline plane, with its extension 241 pressing against the abutment 246, the abutment having pressed down the extension 241 to raise the slotted end 244 of 35 the link. In this position of the parts the spring 242 is stretched or placed under tension. As the gripping and transferring jaws approach the folding-box the cam 238 acts, the rack-bar 229 is pulled downward, and the 40 pinion 104 is turned in the direction required to swing the pressing and lifting arm 77 toward the folding-box. When the rack-bar 229 commences to descend, the spring 242 tends to pull the extension 241 of the link 239 45 upward against the abutment 246, and therefore the rack-bar 230 is caused to descend a slight distance more rapidly than the rack 229 for the purpose of turning the pinion 105 and causes the folder-wings 80 and 81 to close 50 as the arm 77 rises. The positive down motion of the rack-bar 229 will quickly cause the extension 241 to leave the abutment 246,

and at this time the link 239 is approximately horizontal, due to the power of the spring 242, which has acted on the link 239 to lower 70 the rack-bar. The link will be held approximately horizontal by the spring, as in Fig. 4, for a definite length of time. The two rack-bars now descend in unison, due to the fact that the spring holds the link stiffened and 75 nearly horizontal; but the rack-bar 230 is somewhat lower than the rack-bar 229, Fig. 4, and the two folder-wings 80 and 81 of the arm 77 are closed or lie in the position shown 80 in Fig. 12. As the two rack-bars descend in 85 unison the lower end of the rack-bar 230 will strike a lateral pin 247 on the inner end of a lever 248, which yields but retards the downward motion of this rack-bar, while the other rack-bar continues to descend more swiftly, 90 due to the positive action of the cam 238 on the arm 236 of the bell-crank lever which connects with the rack-bar 229. The rack-bar 229 acts on the pinion 104 to swing the pressing and lifting arm 77 into the folding-box. 95 As this occurs the folder-wings 80 and 81 will be slowly spread open, for although the down motion of the rack-bar 230 is retarded by this slowly-yielding inner end of lever 248, yet said rack-bar slowly descends and slowly 100 turns the pinion 105. The lever 248 is pivoted between its ends, as at 249, and at its outer extremity carries a roller-stud bearing against the periphery of the cam 238, which acts to positively raise and lower the rack-bar 229. The periphery of this cam is provided with two notches 250 and 251, Fig. 4, 105 for a purpose hereinafter explained. When the pressing and lifting arm 77 rests in the folding-box and cannot move farther downward, the roller-stud at the outer end of the lever 248 can enter the notch 251 of the cam 238, and as the rack-bar 229 cannot farther descend the spring 242 again acts to move the link 239 on the pivot-stud 240, thereby further moving the rack-bar 230 and the inner 110 end of the lever 248 downward to slightly turn the pinion 105 and cause the wings 80 and 81 of the arm 77 to close and form the 115 downfolds 7, Fig. 33, at the ends of the wrapper. The instant the downfolds are formed the roller-stud at the outer end of the lever 248 rides out of the notch 251 onto the concentric periphery of the cam 238, thereby 120 slightly swinging the lever 248 and causing it to raise the rack-bar 230, throw the link 239 into an inclined position, stretch the spring 242, turn the pinion 105, and open the folder-wings 80 and 81, so that the oscillating tuckers or side-angle folders can operate as 125 before explained. While the tuckers or side-angle folders 74 and the end-folder wings 73 of the folding-box are operating the pad 84 of the arm 77 is pressing upon the adhesive margin of the binder to secure the wrapper 130 and the folder-wings 80 and 81 of this arm remain open. After the tucks or side-angle folds 9, Fig. 34, and the upturned end folds 10, Fig. 35, are formed the link 239 will stand 135

in an inclined position, owing to the rack-bar 230 having been elevated by the action of the lever 248 to open the folder-wings 80 and 81. The parts remain in this position until the 5 roller-stud at the outer end of the lever 248 reaches the notch 250 in the periphery of the cam 238, whereupon the spring 242 will act to pull the extension 241 upward, thereby lowering the rack-bar 230 to close the folder-wings 10 80 and 81, while the rack-bar 229 remains motionless. The folder-wings 80 and 81 are thus caused to grip and hold the wrapped package, and at this instant the cam which operates the bell-crank-lever arms 234 and 236 15 commences to act and the two rack-bars ascend in unison, due to the fact that the spring 242 has forced the link 239 to a horizontal position, in which position it is stiffened, so that both rack-bars are compelled to rise together 20 until the extension 241 of the link 239 is arrested by the abutment 246, whereupon the link 239 will be forced to the inclined position represented in Fig. 13, so that the rack-bar 230 is raised, the pinion 105 is turned, 25 and the links 100 and 101, Fig. 12, are actuated to open the folder-wings 80 and 81 of the arm 77 for the purpose of releasing the wrapped package, so that it can be pushed from the arm onto the rear section 88 of the 30 receiving-table through the medium of the pusher 87. Subsequently the operations are the same as hereinbefore described in detail.

The pusher 87 is positively operated at predetermined intervals in the following manner: The pusher is provided with a shank 252, dovetailed to suitable guides and engaged with the upper end of a crank-arm 253, Figs. 3 and 27, extending from a sleeve 254, which is also provided with a downwardly-projecting crank-arm 255. The sleeve is mounted on a fixed stud 256, and the lower end of the crank-arm 255 is provided with a roller-stud 257, acted upon by a cam-race 258 in cam 192, and of such suitable construction that when 45 the pressing and lifting arm lies in the slot 85 of the receiving-table the crank-arm 255 will be moved forward, while the crank-arm 253 will be moved rearward, thus pushing the article from the pressing and lifting arm onto 50 the section 88 of the receiving-table, immediately after which the motion of the said crank-arms will be reversed and the pusher will be retracted to its normal position. The wrapped packages are delivered to the chute 55 89, as before explained, by which they are carried or conveyed to a suitable receptacle or to the point desired.

Inasmuch as any person skilled in the art can construct cams suitable to effect the movements of the working parts herein described, I do not deem it necessary to explain in detail the exact contour of the cams illustrated, nor do I wish to be understood as confining myself to any particular form of cams, in that 60 65 it is possible to obtain the same results by cams of suitable but different form from those shown.

Having thus described my invention, what I claim is—

1. In a package-wrapping machine, the combination of a magazine for containing articles of merchandise, means for discharging the articles from the magazine, a reel for carrying a web of wrapping material, mechanism for drawing the web longitudinally, a cutter for severing a wrapper-section from the web, a folding mechanism, two swinging and co-operating gripping-jaws for transferring the article and wrapper-section in a circular path from near the magazine to said folding mechanism, devices for opening, closing and swinging said jaws, a part of the folding mechanism consisting of an arm which lifts the wrapped article and deposits it at a point from whence it may be removed, substantially as described.

2. In a package-wrapping machine, the combination of a magazine for containing articles of merchandise, means for discharging the articles from the magazine, a reel for carrying a web of wrapping material, mechanism for drawing the web longitudinally, a cutter for severing a wrapper-section from the web, a folding mechanism, two swinging and co-operating gripping-jaws for transferring the article and wrapper-section in a circular path from near the magazine to said folding mechanism, a part of the folding mechanism consisting of a swinging arm which lifts the wrapped article and places it at a point from which it may be removed, and mechanisms for swinging said arm and operating said gripping-jaws, substantially as described.

3. In a package-wrapping machine, the combination of a magazine for containing articles of merchandise, means for discharging the articles from the magazine, a support for the articles discharged from the magazine, a reel for carrying a binder-web, means for carrying webs of foil and paper, two pair of reciprocatory nippers which seize the binder-web and the webs of foil and paper, respectively, and draw them longitudinally, a cutter for severing the webs to form a wrapper-section of which one part is a binder, means for moving one pair of the nippers a greater distance than the other to shift and position the binder relatively to the foil and paper parts of the wrapper-section, a folding mechanism, and means for transferring the article and the wrapper-section from said support to said folding mechanism, substantially as described.

4. In a package-wrapping machine, the combination with a folding-box having devices for folding parts of the ends of a wrapper inclosing an article of merchandise, of a hollow arm having folding-wings which enter the box or chamber and serve to fold parts of the wrapper and to seize and remove the wrapped article from the box, devices located in said arm and connected with the folding-wings thereof to actuate the same from within the arm, and means for operating the wing-actuating

devices within said arm and operating the latter to remove the wrapped article from said box, substantially as described.

5. In a package-wrapping machine, the combination of longitudinal folders, a folding-box having oscillatory tuckers, or side-angle folders at its corner portions, and opening and closing folding-wings at its ends, a swinging arm having opposing opening and closing folding-wings, and mechanisms for swinging the arm, operating the tuckers or side-angle folders, the end folding-wings of the folding-box and the folding wings of said arm, substantially as described.

15 6. In a package-wrapping machine, the combination of a magazine, means for supporting wrapping material, means for moving the wrapping material longitudinally, a cutter for severing the wrapping material into a wrapper, means for discharging an article from the magazine into proper relation to the wrapper, a folding-box having devices for folding parts of the ends of the wrapper, means for longitudinally folding the wrapper, mechanism for transferring the article and the wrapper in fixed relation to each other to the folding-box, an arm having devices which serve to fold parts of the wrapper and to seize and remove the wrapped article from the folding-box, and means for operating the arm to remove the wrapped article from said box or chamber, substantially as described.

7. In a package-wrapping machine, the combination with means for longitudinally folding a wrapper, and a folding-box having folding devices for folding parts of the ends of the wrapper inclosing the article of merchandise, of an arm having pivoted folder-wings at its end portions, devices arranged in said arms for operating the wings to fold parts of the wrapper and to subsequently seize and remove the wrapped article from the folding-box, and mechanism for swinging said arm and actuating the devices therein contained which operate the pivoted wings, substantially as described.

8. In a package-wrapping machine, the combination with means for longitudinally folding a wrapper, and a folding-box having folding devices for folding parts of the ends of the wrapper to inclose the article of merchandise, of an arm having pivoted folder-wings at its end portions, devices arranged in said arm for operating the wings to fold parts of the wrapper and to subsequently seize and remove the wrapped article from the folding-box, and mechanism for swinging said arm and actuating the devices therein contained which operate the pivoted wings, said arm constructed between the wings to press upon the wrapped article in the folding-box to secure an adhesive part of the wrapper, substantially as described.

9. In a package-wrapping machine, the combination with a magazine, and means for supporting wrapping material, of means for moving the wrapping material longitudinally, a

cutter for severing the wrapping material into a wrapper, means for discharging an article from the magazine into proper relation to the wrapper, means for longitudinally folding the wrapper, a folding-box having devices for folding parts of the ends of the wrapper, mechanism for transferring the article and the wrapper in fixed relation to each other to the folding-box, an arm having folder devices which serve to fold parts of the wrapper and to seize and remove the wrapped articles from the folding-box, and a rack-and-pinion mechanism for operating the arm and its folder devices, substantially as described.

10. In a package-wrapping machine, the combination with longitudinal folders, and a folding-box having folding devices for folding parts of the ends of a wrapper to inclose an article of merchandise, of an arm having pivoted folder-wings at its end portions, devices arranged in said arm for operating the wings to fold parts of the wrapper and to subsequently seize and remove the wrapped article from the folding-box, and racks and pinions for swinging said arm and actuating the devices therein contained which operate the pivoted wings, said arm constructed between the wings to press upon the wrapped article in the folding box or chamber to secure an adhesive part of the wrapper, substantially as described.

11. In a package-wrapping machine, the combination of a folding box or chamber, means for placing the wrapping material and the article to be wrapped in the folding box or chamber, a swinging arm constructed to press upon an adhesive part of the wrapping material to secure the same and having folder-wings to fold parts of the wrapper and to subsequently remove the wrapped article from the folding-box, and means for swinging said arm and operating its folder-wings, substantially as described.

12. In a package-wrapping machine, the combination of longitudinal folders, a folding-box, means for placing the wrapping material and the article to be wrapped in the folding-box, a swinging arm constructed to press upon an adhesive part of the wrapping material to secure the same and having folder-wings to fold parts of the wrapper and to subsequently remove the wrapped article from the folding-box, means for swinging said arm and operating its folding-wings, and a receiving-table upon which the swinging arm deposits the wrapped article, substantially as described.

13. In a package-wrapping machine, the combination of longitudinal folders, a folding-box, means for placing a wrapper and an article to be wrapped in the folding-box, a swinging arm constructed to press upon an adhesive part of the wrapper to secure the same and having folder-wings to fold parts of the wrapper and to subsequently remove the wrapped article from the folding-box, and means for swinging said arm and opening and closing its folder-wings, a receiving-table upon

- which the swinging arm deposits the wrapped article, and a pusher for pushing the wrapped article from said arm, substantially as described.
- 5 14. In a package-wrapping machine, the combination of longitudinal folders, a folding-box, means for placing a wrapper and an article to be wrapped in the folding-box, a swinging arm constructed to press upon an adhesive part of the wrapper to secure the same and having folder-wings to fold parts of the wrapper and to subsequently remove the wrapped article from the folding-box, means for swinging said arm and opening and closing its folder-wings, a receiving-table having a slot through which the arm passes, and a pusher sliding on the receiving-table for pushing the wrapped article from said arm, substantially as described.
- 10 15. In a package-wrapping machine, the combination of a table, reels for carrying webs of wrapping material, guide-plates between which the webs pass from said table, reciprocating nippers for gripping the leading ends 70 of the respective webs and drawing them longitudinally, means for placing the article to be wrapped in proper relation to the webs, a cutter for severing a wrapper from the superimposed webs, a folding mechanism, and a transferring mechanism for transferring the article and the wrapper to the folding mechanism, substantially as described.
- 15 16. In a package-wrapping machine, the combination of a table, reels for carrying webs 75 of wrapping material, guide-plates having notches in their leading edges and between which the webs pass from said table, reciprocating nippers constructed to enter the notches and grip the leading ends of the webs to draw them longitudinally, means for placing the article to be wrapped in proper relation to the webs, a cutter for severing a wrapper from the superimposed webs, a folding mechanism, and a transferring mechanism 80 for transferring the article and the wrapper in fixed relation to each other to the folding mechanism, substantially as described.
- 20 17. In a package-wrapping machine, the combination with a folding-box containing 85 folders for folding parts of a wrapper, of a movable clamp forming part of the folding-box, and means for inserting a wrapper and an article into the folding-box and acting on a part of said movable clamp, whereby the latter is caused to firmly grip and hold the wrapper and article in fixed relation during the folding operation, substantially as described.
- 25 18. In a package-wrapping machine, the combination with a folding-box containing 90 folders for folding parts of a wrapper, of a pivoted clamp-jaw having a tailpiece and forming part of the folding-box, and means for inserting a wrapper and an article into the folding-box and acting on the tailpiece of the clamp-jaw, whereby the latter is caused 95 to firmly grip and hold the wrapper and article in fixed relation during the folding operation, substantially as described.
- 30 19. In a package-wrapping machine, the combination with means for supporting webs of wrapping material, and a cutter for severing wrappers therefrom at regular intervals, of two pairs of horizontally-reciprocating nippers for seizing and drawing the respective webs horizontally, means for closing the nippers upon the leading ends of the webs, means for opening the nippers after they have shifted a wrapper in relation to an article to be wrapped, means for reciprocating the nippers, and means for folding the wrapper, substantially as described.
- 35 20. In a package-wrapping machine, the combination with means for supporting webs of wrapping material, and a cutter for severing wrappers therefrom at regular intervals, of two pairs of longitudinally-reciprocating nippers for seizing and drawing the respective webs longitudinally, means for closing the nippers upon the leading ends of the webs, means for opening the nippers after they have shifted a severed wrapper in relation to an article to be wrapped, mechanisms for reciprocating the two pairs of nippers, and means for folding the wrapper, substantially as described.
- 40 21. In a package-wrapping machine, the combination of reels for carrying webs of wrapping material, of which one web is a binder-web, a magazine, means for discharging an article from the magazine, reciprocatory mechanism for seizing the leading ends of the webs and pulling them longitudinally over the said article, a cutter for severing a wrapper from the webs, and means for operating a part of said reciprocating mechanism to adjust the binder relatively to the other portions of the wrapper severed from the webs, substantially as described.
- 45 22. In a package-wrapping machine, the combination of reels for carrying webs of wrapping material, of which one web is a binder-web, a magazine, means for discharging an article from the magazine, a pair of reciprocating nippers for seizing the leading ends of the webs and pulling them longitudinally, a cutter for severing a wrapper from the webs, one pair of said nippers moving independently of the other pair to adjust the binder relatively to the other portions of the wrapper severed from the webs, and a folding mechanism, substantially as described.
- 50 23. In a package-wrapping machine, the combination with reels for carrying webs of wrapping material, of which one web is a binder-web, a magazine, means for discharging an article from the magazine, a folding mechanism, and means for severing a wrapper-section from the webs, of two pair of reciprocating nippers for pulling the respective webs longitudinally, one pair being movable at a certain time while the other pair is sub-

stantially stationary, for adjusting the binder of the wrapper-section relatively to the other portions thereof, substantially as described.

24. In a package-wrapping machine, the combination with reels for carrying webs of wrapping material, a magazine, means for discharging an article from the magazine, a folding mechanism, and means for severing a wrapper-section from the webs, of reciprocating nippers for pulling the respective webs longitudinally, means for moving one pair of the nippers faster than the other, and means for moving one pair slightly after the other pair has ceased to move, for the purpose of shifting and adjusting the binder in proper relation to the other portions of the wrapper-section, after the wrapper-section is severed from the webs, substantially as described.

25. In a package-wrapping machine, the combination with reels for holding webs of wrapping material, a magazine for containing articles of merchandise, and means for discharging the articles successively from the magazine, of longitudinally-moving slides having fixed nipper-jaws, movable nipper-jaws mounted on the slides, mechanisms for moving the slides back and forth and operating the movable jaws at regular intervals, a folding mechanism, and means for transferring an article and a wrapper to the folding mechanism, substantially as described.

26. In a package-wrapping machine, the combination with a magazine for containing articles of merchandise, and means for successively discharging the articles therefrom, of reels for carrying webs of wrapping material, one of which webs is a binder-web having an adhesive margin, a fluid-tank, a moistening-disk for moistening the adhesive margin of the binder-web, means for supplying fluid from the tank to the moistening-disk, longitudinally-movable nippers for drawing or pulling the webs longitudinally, a cutter for severing the webs into wrappers, a folding mechanism, and means for transferring an article and a wrapper from a point adjacent to the magazine to the folding mechanism, substantially as described.

27. In a package-wrapping machine, the combination with a table, reels for carrying the webs of wrapping material, mechanism for drawing or pulling the webs longitudinally over the table, guide-plates between which the webs pass, a cutter for severing the webs into wrapper-sections, a rocking pressing-finger which presses the webs down upon the said table after the cutter has severed a wrapper from the webs, a folding mechanism, and means for transferring an article and a wrapper from a point adjacent to the magazine to the folding mechanism, substantially as described.

28. In a package-wrapping machine, the combination with a magazine for containing articles of merchandise and means for successively discharging the articles from the magazine, of reels for carrying webs of wrap-

ping material, longitudinally-movable nippers for drawing or pulling the webs longitudinally, a cutter for severing the webs into wrappers, a table over which the webs pass to the cutter, a folding mechanism, means for transferring an article and a wrapper to the folding mechanism, a rock-shaft carrying a brake-arm and a pressing-finger, the brake-arm acting at intervals to arrest one of the reels, and the pressing-finger acting to press the webs upon the table at regular intervals, and means for operating the rock-shaft, substantially as described.

29. In a package-wrapping machine, the combination with a folding-box having movable end-folder wings, of a toothed disk, links eccentrically connecting the end-folder wings with the toothed disk, a bell-crank lever having one end provided with a rack engaging the toothed disk, a trip-dog engaging the other arm of the lever to pull it in one direction and lower the rack, and a spring for raising the rack after the trip-dog has been tripped from engagement with said lever, substantially as described.

30. In a package-wrapping machine, the combination with a folding-box, of oscillatory tuckers or side angle-folders at the corners thereof, pivoted folder-wings at the ends of the box, rack-and-pinion mechanism for oscillating the tuckers or side angle-folders, a toothed disk, links eccentrically connecting the end-folder wings with the toothed disk, a bell-crank lever having one arm provided with a rack engaging the toothed disk, a trip-dog for engaging the other arm of the lever and pulling it in one direction to lower the rack, and a spring for raising the rack after the trip-dog has been tripped from engagement with said lever, substantially as described.

31. In a package-wrapping machine, the combination with a folding-box having tuckers or side angle-folders and end-folder wings, and means for operating the same, of a hollow swinging arm provided with pivoted folder-wings, and mechanism for swinging said arm and opening and closing its folder-wings during its swinging motion, substantially as described.

32. In a package-wrapping machine, the combination with a folding-box having tuckers or side angle-folders and end-folder wings, and means for operating the same, of a hollow swinging arm provided with pivoted folder-wings, racks and pinions for swinging said arm and opening and closing its folder-wings during its swinging motion, and means for independently operating the racks, substantially in the manner and for the purposes set forth.

33. In a package-wrapping machine, the combination with a folding-box, and a receiving-table in proximity thereto, of a swinging, pressing and lifting arm having folder-wings which form folds in the ends of a wrapper, and subsequently grip the wrapped package,

lift it out of the folding-box and place it substantially on a level with the receiving-table, mechanism, substantially as described, for swinging said arm and operating its folder-wings, and a pusher for pushing the package off the pressing and lifting arm onto a part of the receiving-table, substantially as described.

34. In a package-wrapping machine, the combination with a magazine, means for successively discharging articles from the magazine, means for moving wrapping material into position relative to each article discharged from the magazine, a folding-box, and means for transferring an article and a wrapper to the folding-box, of vertical rack-bars, a link pivoted intermediate its ends to one of the rack-bars and loosely connected at one extremity with the other rack-bar, a spring connecting the opposite extremity of the link with the rack-bar to which said link is pivoted, pinions engaging the rack-bars, a pressing and lifting arm rigid with one pinion, folder-wings on said arm, connections between the folder-wings and the other pinion, a cam, a lever engaging the cam and connected with the rack-bar which is rigid with one of the pinions, and a lever acted on at one end by the cam and having the other end lying in the path of the bar which operates the pinion by which the folder-wings are actuated, substantially as described.

35. In a package-wrapping machine, the

combination with a magazine, means for discharging articles successively therefrom, reels 35 for carrying webs of wrapping material, one of which webs is a binder-web having an adhesive margin, a cutter for severing the webs into wrapper-sections, a folding mechanism, and means for carrying an article and a wrapper to the folding mechanism, of a moistening-disk for moistening the adhesive margin of the binder-web, means for raising and lowering the moistening-disk at regular intervals, and means for supplying the said disk 45 with moistening fluid, substantially as described.

36. In a package-wrapping machine, the combination of a support for an article which is to be wrapped, a reel for carrying a web of 50 wrapping material, means for moving the web longitudinally, a cutter for severing a wrapper from the web, a folding-box having folding devices, means for placing an article and a wrapper in the folding-box, and a pressing 55 and lifting arm having folders which serve first to fold end portions of the wrapper and second to grip and lift the wrapped package from the folding-box, substantially as described. 6a

In testimony whereof I have hereunto set my hand this 30th day of December, 1897.

RICHARD A. BERGER.

Witnesses:

ALB. V. RUCKMICH,
KENT HOOPER.
